UNITED STATES PATENT OFFICE.

ORIN P. LIVELY, OF PORTSMOUTH, VIRGINIA.

DISPLAY-STAND.

No. 888,716

Specification of Letters Patent. Patented May 26, 1908.

Application filed October 27, 1905. Serial No. 284,673.

To all whom it may concern:

Be it known that I, ORIN P. LIVELY, a citizen of the United States, residing at Portsmouth, in the county of Norfolk and State of 5 Virginia, have invented a certain new and useful Improvement in Display-Stands, of which the following is a specification.

The principal object of the invention is to provide a display stand suitable either for 10 domestic use as a repository for potted plants and the like or as an accessory of stores or fruit stands.

Another object is to provide a device of the character stated, which shall have considerable capacity in respect to the space it occupies.

Another object is to provide an expandible rack or stand composed of duplicate parts, which can be conveniently assembled or 20 moved and when not in use folded together into small compass.

To these and other ends hereinafter stated, the invention consists in the novel construction, arrangement and combinations of parts 25 hereinafter described and defined in the claims hereto appended.

The nature, characteristic features and scope of the invention will be more clearly understood by reference to the following description taken in connection with the accompanying drawing, forming part hereof and wherein—

Figure 1, is a perspective view of a display stand embodying features of my invention. 35 Figs. 2, 3, 4, and 5, are details which shall be referred to in the course of the description.

Referring to the drawings, 1, represents the main support consisting of a central rod or standard. The standard 1, is provided at 40 or near the top with an overhang or projection 2, and the shelf members or brackets radiate from the standard and are pivotally attached to the projection 2. 3, are angularly disposed legs or members, which carry 45 the shelves and they are formed or provided with laterally extended flatheads 4. The latter are cut away on one side as at 5, to admit of a hinge connection 6, with the next adjoin-

ing head as will be apparent upon inspection of Fig. 2. The central one of the members 3, 50 is rigidly connected to the projection 2, and the other members are hinged with relation to each other.

7, are brace rods disposed near the bottom of the standard intermediate the legs or 55 members 3, and the central support, and they are formed or provided at their inner ends with hinge members 8, connected with one another and with a lip or projection 9, on the standard. This is clearly shown in 60 Figs. 3 and 5.

10, are angle pieces secured in any suitable manner to the legs or members 3, and they serve to carry the shelves. The latter may be of any approved form, the drawing illus- 65 trating removable trays 11.

It will be manifest from the foregoing description and the illustration, that upon removing the trays 11, the parts may be folded together in small compass, as shown 70 in Fig. 4.

It will further be manifest that the capacity of the stand can be varied by adding or removing one or more of the arms or legs 3.

Having described the nature and objects 75 of my invention, what I claim as new and desire to secure by Letters Patent is:—

An expandible knock-down display stand consisting of a central support or standard having an overhang or projection, a built-up 80 series of pivotally connected angle irons or shelf members radiating from the standard and pivotally connected as a unit to said projection so that they may close upon one another or be brought in parallelism, brace 85 rods pivotally connecting the shelf members and standard, and angle pieces to receive the shelves.

In testimony whereof I have hereunto signed my name in the presence of two sub- 90 scribing witnesses.

ORIN P. LIVELY
